Primary Examiner — Kevin K Rudzinski*Assistant Examiner* — Darcy Fabre(57) **CLAIM**

The ornamental design for a running belt, as shown and described.

DESCRIPTION

FIG. 1 is a front, right and bottom perspective view of a running belt showing my new design;

FIG. 2 is a rear, left and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a front, right and top perspective view of the running belt, shown in condition of use.

The broken lines are representing stitching of the running belt and the broken lines form no part of the claimed design.

1 Claim, 5 Drawing Sheets(56)
